UNITED STATES PATENT OFFICE.

ELBRIDGE G. MATTHEWS, OF OAKHAM, ASSIGNOR TO FRANKLIN F. HOLBROOK AND THOMAS B. EVERETT, OF BOSTON, MASSACHUSETTS.

IMPROVEMENT IN PLOWS.

Specification forming part of Letters Patent No. 123,272, dated January 30, 1872.

To all whom it may concern:

Be it known that I, ELBRIDGE G. MATTHEWS, of Oakham, in the county of Worcester and Commonwealth of Massachusetts, have invented certain new and useful Improvements in Steel Swivel-Plows for general use on level and hill-side ground; and I do hereby declare the following to be a full, clear, and exact description of the same, reference being had to the accompanying drawing which forms a part of this specification, and in which—

Figure 1 represents a plan view of a swivel-plow embracing my improvements. Fig. 2 represents a view of the land-side of same. Fig. 3 represents a rear view. Fig. 4 represents an under-side view of the mold-board, share, and frog. Fig. 5 represents an upper-side view of the mold-board and share. Fig. 6 represents a transverse section of the mold-board, share, and frog at line A B, Figs. 5 and 6. Fig. 7 represents a perspective view of the dog-brace separate from the plow. Fig. 8 represents a section of the dog-brace at line C D, Fig. 7; and Fig. 9 represents, on a somewhat larger scale, a transverse section of the standard-shoe.

This invention relates to certain improvements in the construction of the various parts of a swivel-plow and in the combination of said parts with each other, whereby a stronger, lighter, and more efficient swivel-plow for general use is obtained, while the cost of manufacture is reduced.

In the drawing, the parts marked A represent the plow-beam. B indicates the mold-board, which may be pressed from sheet-steel or made from any other suitable material. C indicates the share or point, which is pressed from sheet-steel of proper thickness. D D' indicates the standard; E indicates the frog; F indicates the dog-brace; and G, the sward-cutter. H H indicate steel land-side facings, which are attached to each side of the lower portion of the standard D D', as illustrated. These facings, being of steel, can be made quite thin and light, while their hardness prevents the rapid wearing away of the parts, and also retains a smooth bright surface. The lower part of the standard is formed with ribs, and the facings H secured to said ribs by screws or rivets a. The bottom of the standard is shod

with a peculiarly-constructed shoe, I, which is provided with two upward-projecting longitudinal flanges, c c, which fit up between the lower edges of the facing pieces H and the lower edge of the standard-foot, which latter is grooved out for their reception. The shoe is secured in place by screw-bolts set up through it from the under side. This shoe I can readily be replaced when worn out. The frog E is made of malleable iron, and is formed in the peculiar manner as indicated in the drawing. It is provided with an opening in its lower part to receive the pivot at the forward part of the standard, and with backward-projecting ears E', which support the mold-board, while its lateral edges d d are turned upward so as to fit up against and support the share, which latter is secured to the edges or lips d by screws, bolts, or rivets e, in the manner shown. The mold-board B extends down over the frog E with a long point, B', and is secured to the frog by screws or rivets f near its edge, which fits against the inner edge of the share. Strengthening flanges g are formed on the rear edge of the frog, while a central longitudinal flange or bridge-bar, h, is formed at its central part, extending from the shoulder of the frog back to the flange g, and provided with a suitable opening to receive the hooked end of the dog-brace rod J, as illustrated. The frog-point K is formed separate from the other portion of the frog E, and is brazed on or otherwise rigidly secured to the point of the share, and is joined to the frog by a dowel-pin and bevel-joint, as shown in Fig. 2. The share C is formed of two supporting and cutting wings, C', which diverge from the point C' and fit along the edges of the front part B' of the mold-board, resting upon the edges or lips d of the frog E, to which they are secured in the manner before stated. The share C is stamped from sheet-steel and pressed to the proper curvature by suitable dies, the supporting edges b being rolled upward to correspond with and meet the curve of the mold-board; and it will be observed that the form of the share is such that a number of shares can be cut from a sheet of metal with but very little waste of stock, as the point of one share may be cut from the space left by the V or angle of the other. I am enabled to

use this shape of share by constructing the frog E of the peculiar form shown, with its side lips or curved edges for supporting the inner edges of the share, thus obviating the necessity of recessing the edge of the mold-board to receive and support the edges of the share, as has heretofore been practiced. The dog-brace F is made of malleable iron, and is of the peculiar form illustrated in Figs. 7 and 8, its two side bars being formed angular or with flanges K along their outer edges, and the pintle l at the lower end being formed hollow, as shown. The upper ends i are turned forward so as to hook into the eyes upon the under side of the mold-board. These ends are also hollowed out upon their upper sides, so that all parts of the brace are brought nearly to a uniform thickness, which insures lightness and a more perfect malleability of the iron, and also prevents the cracking of the castings, when cooling, by unequal shrinkage. A bolt, J, extends from the central flanged cross-bar F' of the dog-brace F to the under side of the frog E, to which its forward end is secured by being hooked into an opening in the flange h, while its rear end is passed through an opening in the cross-bar of the dog-brace F, and is provided with a nut, j, which is turned up against the outside of the cross-bar in the manner illustrated. The rod J serves to hold the dog-brace F in position, and thereby connect the mold-board with the standard and retain the supporting or swivel pivots in place. The dog-brace is arched outward somewhat in order to render its strength greater, and to enable it the better to withstand the strain of the rod J. The mold-board may be held up to the beam A by means of a hook, L, in the ordinary manner, and the handles of the plow secured as usual to the rear part D' of the standard. The sward-cutter G is a rotary cutter, and is attached to the beam of the plow in such a manner as to be adjustable laterally and vertically. A sliding plate, m', is arranged between suitable guides on the under side of

the beam A, and the cutter-supporting standard M is cast upon the under side of said plate. The bearing pieces N which contain the bearings of the cutter-spindle are arranged in vertical grooves formed within the standard M in such a manner that said pieces can be moved up or down to adjust the height of the cutter, and when so adjusted the parts are held in position by the screws or bolts m. A lever, O, is pivoted to one side of the slide-plate M', and fulcrumed on a suitable pin, n, on the side of the beam. Said lever extends back to the rear of the plow, and by means of the said lever the operator is enabled to move the sward-cutter laterally to adjust it to the proper position when the plow is reversed. Any suitable ratchet or catch device may be combined with the lever for holding the parts in any adjusted position.

Having described my improvements in steel swivel-plows, what I claim therein as new and of my invention, and desire to secure by Letters Patent, is—

1. The frog E, provided with the curved share-supporting edges or lips d d, substantially as described, and for the purpose set forth.

2. The combination, with the plow-beam A and circular or rotary cutter G, of a laterally-adjustable frame or supporting standard M M', substantially as and for the purposes set forth.

3. The combination, with the laterally-adjustable supporting standard M M' and rotary sward-cutter G, of the vertically-adjustable bearing pieces N and holding-screws or bolts m, substantially as and for the purposes set forth.

4. The combination, with the laterally and vertically adjustable cutter-supporting frame M M' P and plow-beam A, of the hand-lever O, for adjusting the cutter from the rear of the plow, substantially as shown and described.

ELBRIDGE G. MATTHEWS.
